WALKER & JOCKE(57) **CLAIM**

The ornamental design for an appliance handle as shown and described.

DESCRIPTION

FIG. 1 is a top right front perspective view of the appliance handle showing my new design, with features shown in broken lines forming no part of the claimed design and with the lines having a pair of short dash lines between each pair of long dash lines being boundaries of the claimed design.

FIG. 2 is a left side view thereof.

FIG. 3 is a front view thereof.

FIG. 4 is a right side view thereof.

FIG. 5 is a back view thereof.

FIG. 6 is a top view thereof; and,

FIG. 7 is a bottom view thereof.

The broken lines in the drawings form no part of the claimed design and the lines having a pair of short dash lines between adjacent long dash lines are boundaries of the claimed design.
